James E. Jones, Toledo, Ohio, assignor to The
Hetrick Manufacturing Company, Toledo,
Ohio, a corporation of Ohio

Application September 25, 1952, Serial No. 21,586

Term of patent 14 years

(Cl. D15—8)

To all whom it may concern:

Be it known that I, James E. Jones, a citizen of the United States and a resident of Toledo, Lucas County, Ohio, have invented a new, original, and ornamental Design for a Chair, of which the following is a specification, reference being had to the accompanying drawing, forming a part thereof.

In the drawing:

Figure 1 is a front perspective view of a chair, showing my new design; and

Figure 2 is a rear end elevation of the chair.

I claim:

The ornamental design for a chair, as shown.

JAMES E. JONES.
